DESIGN FOR A GAME DEVICE

Harry E. Hymer, Harrison, N. Y.

Application March 8, 1939, Serial No. 83,431

Term of patent 7 years

To all whom it may concern:

Be it known that I, Harry E. Hymer, a citizen of the United States, residing at Harrison, in the county of Westchester and State of New York, have invented a new, original, and ornamental Design for a Game Device, of which the following is a specification, reference being had to the accompanying drawing, forming a part thereof.

Fig. 1 is a plan view of a game device showing my new design; and

Fig. 2 is an elevational view thereof.

I claim:

The ornamental design for a game device, substantially as shown.

HARRY E. HYMER.
